[57] CLAIM

The ornamental design for the bottle, as shown and described.

DESCRIPTION

FIG. 1 is a front perspective view of a bottle showing our new design, the rear and sides of the bottle are the same in appearance as the front side shown except for the conventional screw threading on the bottle neck;

FIG. 2 is a top view thereof; and,

FIG. 3 is a bottom view thereof.

The stipple shading in the drawings is used to indicate an opaque surface. The graduated degree of stipple shading is understood to illustrate that the surface of the bottle becomes increasingly more opaque toward the bottom of the bottle.
